UNITED STATES PATENT OFFICE.

EMIL GORNICEC, OF YOUNGSTOWN, OHIO.

COMBINATION-LOCK.

1,326,191.

Specification of Letters Patent. Patented Dec. 30, 1919.

Application filed May 23, 1918. Serial No. 236,082.

To all whom it may concern:

Be it known that I, EMIL GORNICEC, a citizen of the United States, residing at Youngstown, in the county of Mahoning and State 5 of Ohio, have invented certain new and useful Improvements in Combination-Locks, of which the following is a specification.

This invention relates to combination locks, more particularly to an improvement 10 in lock structure set forth in Letters Patent No. 1,173,348, granted to me February 29, 1916, and not only embodies the objects and advantages set forth in the Letters Patent referred to but has for its further object to 15 provide the lock with means, in a manner as hereinafter set forth for maintaining the shackle in an open position, when required, thereby preventing the lock from accidentally closing.

20 A further object of the invention is to provide a lock, in a manner as hereinafter set forth, including a locking arm arranged in the path of a series of locking disks when the lock is open, and to further provide 25 means associating with said locking arm for shifting it clear of the locking disk to enable the convenient closing of the lock when occasion so requires.

The invention further relates to a combination lock which is simple in its construction and arrangement, strong, durable, efficient in its use and comparatively inexpensive.

With the foregoing and other objects in 35 view the invention consists of the novel construction, combination and arrangement of parts as hereinafter more specifically described and illustrated in the accompanying drawing, wherein is shown an embodiment 40 of the invention, but it is to be understood that changes, variations and modifications can be resorted to which come within the scope of the claims hereunto appended.

In the drawings wherein like reference 45 characters denote corresponding parts throughout the several views:

Figure 1 is a front elevation of a combination lock in accordance with this invention.

Fig. 2 is a rear elevation.

50 Fig. 3 is a rear elevation, with the back plate removed showing the elements in position when the lock is closed.

Fig. 4 is a similar view showing the position of the elements when the lock is open.

Fig. 5 is a section on line V—V, Fig. 4, 55 with the back plate in position.

Fig. 6 is a sectional detail of the casing.

Fig. 7 is a detail of the locking arm.

Referring to the drawings in detail 1 denotes a casing having a back plate 2, which 60 is maintained in position by crimping over as at 3, the cylindrical body portion 4, of the casing 1. The front wall 5 of the casing 1, has a countersunk opening 6, and formed integral with said front wall 5, is an inwardly extending annular member 7, having a disk 8, formed integral with its inner end. The member 7, and disk 8, forms a 65 pocket 9, having a series of locking disks, not shown, similar to that set forth in the 70 Letters Patent referred to.

The disk 8, has an opening 10, and is also formed with a radially disposed notch 11, which terminates in the slot 12, formed in the member 7. The member 7, and disk 8, 75 is constructed in a similar manner to that set forth in the Letters Patent referred to. A like arrangement, as set forth in said Letters Patent, of the locking disks or tumblers are employed.

80 The body portion 4, of the casing 1, has a pair of openings, one of which is employed for the short arm 13, of the shackle 14, and the other of which is employed for the longer arm 15, of the shackle 14. The inner 85 end of the longer arm 15, is cut-away as at 16, to provide a clearance.

Connected to the end arm of the shackle is a locking arm comprising an L-shaped bar 17, which terminates in a ward 18, disposed in a 90 plane at right angles with the plane of the bar 17. The ward 18, is notched as at 19 to provide a clearance. The bar 17, intermediate its ends, has a lateral extension 20, formed with protuberance 21, 22, disposed 95 at right angles with respect to the extension 20, and which are adapted to engage in grooves 23, formed in the arm 15, whereby the locking arm is connected to the elongated arm of the shackle so as to move with the 100 latter when said arm 15 is shifted in an outward direction. The protuberances 21, 22, engage in the grooves 23, in such manner that the arm 15, can rotate on its longitudinal axes without shifting the locking arm.

105 The upper end of the bar 17, is split as at 24, and bent as at 25 to form a curved lug.

Attached to front wall 5, is an inwardly

extending pin 26, upon which is mounted, a coiled spring 27, the latter having one end extended, as at 28, and bearing against the inner face of the body portion 4, and its 5 other end extended as at 29, and seated in the split 24, against the lug 25. The spring 27, normally maintains the locking arm clear of the slot 12, of the member 7.

Arranged within the body 4, is a lug 30, 10 which constitutes a seat for the inner end of the arm 15, of the shackle 14, when the lock is opened. When the shackle 14 is released and pulled outwardly, the arm 15, can be shifted to seat on the lug 30, and maintained 15 in such position by the action of the spring 27, which prevents accidental closing of the lug.

The reference character 31 denotes a finger piece, for the operating shaft 33 and 32 20 a graduated disk carried thereby. The locking disks or tumblers 34, employed are similar to and arranged in the same manner as that disclosed in Letters Patent No. 1,173,848,

granted to me and it is thought unnecessary to describe same, as this invention relates to 25 the shackle and locking arm carried thereby.

What I claim is:

1. A combination lock comprising a casting having an inwardly extending lug on its body, a shackle extending into said body and 30 adapted to seat on the lug when the shackle is extended and rotated, and a spring controlled locking element connected with the shackle for maintaining the shackle extended when seated on the lug. 35

2. A combination lock comprising a casting having a lug on its body, a shackle extending into said body and adapted to have one of its arms seated on the lug when the shackle is extended and rotated, and a spring 40 controlled locking element connected with said arm and maintaining the shackle on the lug, said shackle being cutaway to clear the lug when the shackle is closed.

In testimony whereof I affix my signature. 45
EMIL GORNICEC.
